COAL FEEDER OR STOKER

William L. Stuyverson, Elkhart, Ind.

Application October 11, 1933, Serial No. 693,049

15 Claims. (Cl. 198—53)

This invention relates to coal feeders or stokers.

One of the objects of the invention is to provide an improved stoker structure which is exceedingly simple in design and is inexpensive to manufacture.

Another object is to provide a structure of the foregoing character which is adapted to feed coal in either a wet, damp, or dry condition.

10 A more specific object is to provide a coal stoker embodying a rotary coal hopper adapted by its rotation to deliver coal in substantially uniform quantities to a feed conduit having hopper-driven conveyor means delivering the coal to the place of consumption.

15 A further object is to provide a closed system for feeding coal whereby slack or very fine and cheap coal may be used with maximum cleanliness and at a minimum of operating expense, and 20 with which combustible coal dust is retained and conveyed to the heating plant where it is burned thereby aiding in fuel saving.

25 Still another object is to provide coal feeding means which eliminates any tendency toward clogging, packing, and arching of the coal to be fed and which reduces wear of the operating parts to the very minimum whereby coal of varying degrees of hardness and coke may be fed with equal efficiency and without materially decreasing the length of life of the structure. More 30 particularly, this invention contemplates an arrangement wherein abrasion action is reduced to the minimum so that very hard coal and coke may be fed by the coal feeding means without 35 detrimental wear effects.

40 A further object is to provide a portable coal stoker readily adjustable to various furnaces or heating plants, the arrangement being such that the structure may be moved from place to place and installed in connection with the furnace or heating plant without the reconstruction of parts of the latter. To the foregoing end, means are provided for adjusting the height of the structure and novel closure means are also provided 45 for closing the ordinary feed door opening of the furnace or heating plant. The arrangement is such that the stoker may be adjusted to the proper height and then set up in connection with the furnace or heating plant by merely opening or removing the usual feed door and moving the structure into operating position.

50 Additional objects are to eliminate the necessity of use of mechanical agitating means, the rotary motion of the hopper serving to agitate and condition the coal for feeding; to provide

an arrangement including but very few parts which are readily adjustable for cleaning, repairing, etc., purposes; to provide a more compact coal feeder structure adapted to hold an increased supply of coal, the arrangement being 5 such that the coal is delivered to a feed conduit connecting with the central portion of the rotary hopper whereby the height of the structure is reduced to the minimum with increased coal storage abilities; to reduce fuel waste to the 10 minimum; to provide an arrangement which may be installed and used with an ordinary home heating plant by an inexperienced and unskilled person; and to provide for positive delivery of the coal to the heating plant regardless of the 15 amount to be delivered within any given time.

Other objects and advantages will become apparent as this description progresses and by reference to the drawings wherein:

Fig. 1 is a vertical sectional view of one form 20 of coal feeding structure embodying this invention, the same being illustrated as applied to a furnace;

Fig. 2 is a front end elevational view of the 25 coal feeding structure shown in Fig. 1;

Fig. 3 is a section taken substantially on line 3—3 of Fig. 1;

Fig. 4 is a section taken substantially on line 4—4 of Fig. 2;

Fig. 5 is an enlarged fragmental side elevational view of means for closing the feed door opening of the furnace;

Fig. 6 is a section taken substantially on line 6—6 of Fig. 5;

Fig. 7 is a detail, vertical sectional view of the 35 adjustable support for the forward part of the structure of Fig. 1;

Fig. 8 is a section similar to Fig. 7, except showing the parts in an inverted position of adjustment;

Fig. 9 is a section taken substantially on line 9—9 of Fig. 3, and showing the structure for latching the hopper door in its closed position;

Fig. 10 is a view similar to Fig. 9 except showing the parts in an unlatched condition;

Fig. 11 is a view taken substantially on line 11—11 of Fig. 10;

Fig. 12 is a rear end elevational view, partially in section, of another form of coal feeding structure embodying the invention; and

Fig. 13 is a section taken substantially on line 13—13 of Fig. 12.

Coal feeding or stoker structure embodying this invention is adapted for use in connection with various forms of heating plants and for purposes 55.

of this description I have shown a form of stoker embodying the invention associated with a conventional form of furnace 10 having a grate 11 and a feed opening 12 adapted to be closed by a door (not shown). According to this invention, the coal feeding structure is particularly adapted to feed coal of any degree of hardness and coke.

The stoker structure shown in Figs. 1 to 11, inclusive, includes a frame 13, a rotatable hopper 14 and a feed conduit 15 having a conveyor 16 therein driven by the rotatable hopper.

The frame 13 (Figs. 1 to 4) includes an integral front section having a lower rectangular portion 20 and an upper, integral and triangular portion 21. The rear frame section takes the form of an upper triangular portion 22 and an integral bottom leg 23 extending centrally from the base of the upper triangular portion 22. The base parts of the upper triangular portions 21 and 22 of the front and rear frame sections are joined together at their opposite sides by side members 24, these parts being secured together by bolt and nut devices 25. The lower part of the rear frame leg 23 and the lower part of the front frame portion 20 are joined together by angularly disposed side members 26 secured at their opposite ends in the same manner as the side members 24. The vertical and horizontal parts of both the front and rear frame sections as well as the side connecting members 24 and 26 are formed to an angle shape for the purpose of adding strength and rigidity to the frame structure as a whole.

The frame 13 (Figs. 1 to 4) is portably carried by front wheels 30 and a rear pilot wheel 31. The wheels 30, 31 are connected to the frame 13 in the following manner: The front wheels 30 are supported by an axle 32 having at its opposite ends tubular casting members 33 adapted to be secured thereto in an upright (Figs. 1, 2, and 7) or inverted position (Fig. 8) by set screws 34. The inner angled portion of the vertical sides of the lower portion 20 of the front frame section are provided with spaced, integral sleeve-like members 35, 36. The casting members 33 receive upright standards 38 (preferably, but not necessarily, tubular) which pass freely through the sleeve-like portions 35, 36 of the upright parts of the front-frame portion 20. The angled portion of the rear frame leg 23 is provided with integral sleeve-like members 39, 40 similar to the sleeve members 35, 36 of the front portion 20, and they slidably receive a tubular standard 41 which is carried by a member 42 with which shank 43 connected to the rear wheel 31 has a swivel connection as at 44. It will be obvious that the vertical position of the frame 13 may be varied by elevating it upward along the standards 38 and 41 and by securing it in its elevated position by tightening set screws 45 carried by the respective sleeve members 35, 36, 39, and 40.

Additional means is provided for lowering or varying the minimum height position of the front end of the frame 13 to accommodate feed door openings of minimum height. The lower ends of the front standards 38 are provided with longitudinally spaced diametrical openings 37, 37' through which the front axle 32 is adapted to be passed. When the casting members 33 are mounted in an upright position as shown in Figs. 1 and 7 the axle 32 is passed through the lower standard openings 37 and the lowermost position of the frame 13 is determined by the frame resting on the upper end of the casting members 33 at a distance above the axle 32 equal substantially to the length of the casting members 33. However,

when the axle 32 is passed through the uppermost standard opening 37', the casting members 33 are inverted so that the portions of the standards projecting beneath the axle 32 are received and supported therein (Fig. 7). Obviously, with the casting members inverted, the frame can be lowered to seat thereon at a point only slightly above the axle 32, thereby reducing the minimum height position of the frame a distance equal substantially to the length of the casting members 33. Adjustment of the frame along the standards 38 and 41 together with the foregoing adjustment accurately insures a proper set-up of the structure with various sizes and kinds of heating plants.

The upper ends or apices of the front and rear triangular frame portions 21 and 22 have ring-like portions 50, 51 that provide aligned openings for support of the feed conduit 15 and the hopper 14 as will be more fully described hereinafter.

The feed conduit 15 (Fig. 1) consists of a pair of joined sections 15^a and 15^b of a combined length sufficient to project the section 15^a entirely through the hopper 14 on the axis of the latter and to project the section 15^b within the furnace 10 at a point substantially above the central portion of the grate 11. The front end of the feed conduit section 15^a passes through the opening in the ring-like part 50 in the front frame section where it is secured to the conduit 35 section 15^b as follows: A collar 52 is screw-threadedly (may be integral if desired) fixed upon the rear end of conduit section 15^b, and the collar 52 is rigidly secured to the ring part 50 by a plurality of studs 53. The ring part 50 and collar 35 52 are provided with aligned and nested recess-and-shoulder connection 53^a which insures proper fitment of these parts and true alignment between the conduit sections 15^a and 15^b. In the foregoing manner the feed conduit 15 as a whole 40 is fixed against movement either axially or rotatably. The rear portion of the conduit 15 projects through the rear wall of the hopper 14 and such end is supported by the structure which rotatably supports the rear part of the hopper as 45 will be more fully explained hereinafter. That part of the feed conduit 15 which is located within the hopper 14 is provided in its upper portion with an opening 54 of relatively small length and width dimensions. Coal, or other fuel that may 50 be fed, is delivered through the opening 54 from the hopper 14 into the feed conduit 15.

The hopper 14 (Fig. 1) is of a cylindrical drum type and it is so mounted that it rotates about the feed conduit 15 at its axis. The opposite ends 60, 61 of the hopper are provided with openings 62 and 63, respectively, for reception of the feed conduit 15. The hopper walls 60, 61 around the openings 62, 63 are reinforced by plates 65. A bearing collar 66 is secured to the outer face 60 of the front hopper wall 60 around the opening 62 and this bearing collar surrounds and finds bearing support upon the adjacent surface of the feed conduit 15. The bearing collar 66 is provided with an oil cup 67 and oil duct 68 for 65 lubrication in an obvious manner.

The outer face of the rear hopper wall 61 also has a bearing collar 69 secured thereto around the opening 63 therein. This bearing collar 69 surrounds and rotates about the rear projecting end of the feed conduit 15 and it finds bearing support in the ring-like part 51 of the triangular portion 22 of the rear frame section. Oil cups 71 and 72 and oil ducts 73 and 74 are associated with the rear bearing collar 69 and the rear 75

frame portion 22 for lubrication of the rotatable bearings in a manner which will be well understood. The rear end of the feed pipe 15 is open and it terminates short of the rear end of bearing collar 69, such collar being provided with a shoulder 69^a against which the rear end of the feed conduit is engaged. The rear end of the bearing collar 69 is also slightly reduced for reception within the ring part 51, providing a shoulder 69^b against which the ring part 51 abuts.

With the arrangement just described, it will be seen that the hopper 14 is not only mounted for rotation about the feed conduit 15, but the rotatable connection between the feed conduit, the hopper 14 and the rear bearing collar 69 also affords additional support for the feed conduit 15 while permitting of the relative rotation just described. The hopper 14 is positively held against axial displacement relative to the feed conduit 15 by collar 75 secured to the feed conduit 15 by set screws 77 in substantially abutting relation with the inner faces of the reinforcing plates 65 next to the front and rear hopper walls 60 and 61. The abutting relation between the shoulders 69^a and 69^b of bearing collar 69 and the rear end of feed conduit 15 and the ring part 51 further serve to position these parts against relative axial displacement.

The interior of the hopper is provided with a shelf-like scoop 78, the same being secured by suitable fastening devices 79 in longitudinal alignment with the opening 54 in the feed conduit 15. In other words, the scoop-like shelf 78 is so located that as the hopper 14 is rotated and the scoop 78 is elevated so as to dump its contents by gravity, such contents will be fed into the feed conduit opening 54. The scoop is of slightly less length than the opening 54 to facilitate the foregoing operation.

The coal, or other fuel to be fed, is deposited in the hopper through a door 80 which is hingedly supported at 81 (Figs. 3 and 9). The door 80 extends throughout the length of the hopper with its opposite ends overlapping the angled rims 82 of the hopper end walls 60 and 61. The lower side edge of the door is adapted to fit snugly and in circumferential alignment with the cylindrical hopper wall as best shown in Fig. 3. The door 80 is adapted to be securely locked in a closed and practically sealed condition by a latch structure which includes an outer handle member 83 rotatably mounted near the lower central and free edge portion of the door. This handle is provided, on the inner side of the door, with a disk 84 to which there are pivotally connected at diametrically opposed points a pair of latch rods 85. The free ends of these rods are slidably supported by door-carried brackets 86. It will be obvious that when the handle 83 is turned to the position shown in Figs. 3 and 9 to latch the door in closed position, the rods 85 will be extended to a point wherein their outer free ends extend beneath the rims 82 of the hopper end walls 60 and 61, thereby preventing outward hinging movement of the door. To unlatch the door (Fig. 10) it is only necessary to rotate the handle 83 in an upward direction to draw the rods 85 inwardly from beneath the hopper wall rims 82, whereupon the door is freed for swinging movement to an open position. The disk 84 is provided with a lug 87 which, in the latched position of the door, extends under the adjacent longitudinal edge of the hopper wall for securely latching the central edge of the door to

the hopper wall (Fig. 9). This structure provides a substantially sealed closure for the hopper opening for the purposes hereinabove stated.

The door handle 83 is held in its door-latching position by a spring 88 secured at one end 5 as at 88^a, to the door with its other and free end projecting toward the free edge of the door. This spring 88 is provided with a notch 89 in its free end and it is so positioned that when the handle 83 is moved to its horizontal latched position 10 (Figs. 3 and 9), such handle engages the spring notch 89 so that the handle is held against accidental movement toward an unlatched position. It will be noted (Fig. 11) that the free and notched end of spring 88 normally extends 15 outwardly away from the door 80 a greater distance than the handle 83 is spaced from the door so that the spring is slightly compressed when the handle 83 is engaged in the notch 89. In this way vibration and other conditions do not 20 affect the latched door and the door remains latched during rotation of the hopper and otherwise until the handle 83 is released and moved to an unlatching position by the operator.

The coal is fed through the feed conduit 15 25 by the screw-type conveyor 16 (Figs. 1 and 3). This conveyor is driven by the hopper in the following manner: The rear bearing collar 69 which is connected to the rear hopper wall 61 extends through the opening in the rear frame part 51 30 sufficiently for securement thereto of a drive plate 90. This drive plate 90 is secured to the bearing collar 69 by a plurality of screw studs 91 and its inner wall is provided with a hub-like part 92 which has a rectangularly-shaped, or 35 other non-circular, opening 93 therein. The rear end or shank 94 of the screw conveyor 16 has a cross sectional shape similar to that of the opening 93 in the drive plate 90, the spiral blade 95 of the conveyor terminating at this rectangular 40 portion slightly rearward of the rear end of the conduit opening 54. The rear end of the conveyor shaft 94 which is received within the opening 93 is slightly smaller than the opening 93 to permit slight play between the parts; and the 45 rear end of the conveyor shaft 94 is secured to the drive member 90 by a screw stud 96 which extends freely through an opening 97 in the drive member 90. The discharge end of the conveyor is free, the conveyor spiral 95 being of a width 50 slightly less than the diameter of the feed conduit 15. This arrangement permits of slight angular movement of the conveyor 16 within the feed conduit 15 whereby the conveyor 16 may freely adjust itself within the feed conduit as 55 the coal is being fed along by the same.

Any suitable means may be employed for driving the hopper 14 and, as shown, I preferably employ an electric motor 100 (Figs. 1 and 2). The motor 100 is connected in any suitable manner to a vertically-swingable arm 101 pivotally connected at 102 to the frame. The other end of the arm 101 is provided with an extension 103 having an opening which receives the lower end of a rod 104 which has its upper end pivotally 65 connected to the frame as at 105. Coil springs 106 are mounted upon the rod 104 on the opposite sides of the arm extension 103 and the position of the arm 101 and the tension of the springs 106 are determined by adjustable thumb nuts 107. 70 In this manner, the motor is provided with a cushioned support and the sprocket chain 108, by which the hopper is driven, is held constantly in an adjustably tensioned condition.

The motor 100 is provided with a drive pinion 75

109 which is drive-connected to a gear 110 rotatably supported by the arm 101. The gear 110 rotates a drive sprocket 111 which is drive-connected with the sprocket chain 108. The forward wall 68 of the drum near its periphery is provided with a drive sprocket 112 secured thereto by bolt and nut devices 113, which sprocket gear is drive-connected with the relatively large sprocket chain 108 so that upon rotation of the drive sprocket 111 by the motor the hopper 14 will be likewise rotated at a relatively slower rate.

The structure may be easily and quickly set up in connection with a heating plant such as the furnace 10 (Fig. 1). The height of the feed conduit 15 may be readily adjusted, as above explained. This adjustment may be carried out either before or after the discharge end of the feed conduit is moved into the furnace 10 above its grate 11. After the structure is moved to its operating position, it is held there by a dog 114 rotatably supported by the wheel axle 32 (Figs. 1 and 2). This dog is provided with a toothed floor-engaging head 115 and a weighted arm 116 so angularly disposed relative to the head that it tends to engage the toothed head with the floor surface. Obviously, with this arrangement, the structure may be moved freely toward the furnace 10 but cannot be moved away without lifting the dog head from the floor. It will be understood that the dog 114 may be similarly associated with the rear or pilot wheel mounting if it is so desired.

The usual door for closing the furnace opening 12 is either opened or removed to permit the feed conduit to be moved into position, and when this is done the opening 12 is closed by a plate 117 carried by the feed conduit 15 as follows (Figs. 1, 5, and 6). A collar member 118 having a lateral surrounding flange 119 is mounted upon the feed conduit 15, being adjustably secured thereto by opposed screw members 120.

The closure plate 117 is adjustably supported upon the flange 119 of the member 118 by a plurality (preferably, but not necessarily, four) of cap screws 121 which pass freely through openings in the plate 117 and are secured to the flange 119. The heads 122 of the screws 121 limit the extent of movement of the plate 117 away from the member 118, and movement of the plate 117 toward the member 118 is yieldably opposed by coil springs 123 surrounding the several studs 121 and confined under slight compression between the plate 117 and flange 119. The openings in plate 117 through which the studs 121 pass are of sufficiently greater diameter than the stems of studs 121 that the plate 117 is free to adjust itself angularly with respect thereto and to the member 118. The plate 117 is also provided with an opening 124 through which the feed conduit 15 passes. The adjustment screws 120 provide for vertical adjustment of the member 118 and plate 117 so as to insure that the plate 117 will be properly positioned over and around the furnace opening 12.

When the structure is moved into operative position with respect to the furnace 10, the closure plate 117 fits over the opening 12 in such a way that it closes the same as effectively as the conventional door. It will be appreciated that variations may exist in the floor surfaces supporting the hopper 14 and the furnace 10, and, to accommodate these variations and insure that the plate 117 will seat uniformly around and over the door opening, the yieldable universal con-

nection above described is provided. The ability of the plate 117 to adjust itself angularly to the cap screws 121 insures this result, while the door is firmly and yieldably pressed into closed position by the springs 123 which may be somewhat compressed. As above explained the dog 114 holds the structure in the foregoing relation to the furnace.

Excess heating of the closure plate 117 and the adjacent parts of the structure is avoided by the provision of a baffle plate 125 formed of metal, or any other suitable material. This baffle plate is detachably supported by the central portion of the closure plate 117 by a U-shaped strap member 126 which has its U-base part welded or otherwise permanently secured to the plate 125 and its U-legs secured to the plate 117 by bolt-and-nut devices 127 (Figs. 1, 5, and 6). The upper left-hand side of the baffle plate 125, as viewed in Fig. 6, is cut away to a slight extent to 20 permit a view of the interior of the furnace through a peep opening 117a in the closure plate 117, which peep opening is adapted to be closed by a door 128. The door 128 is of rectangular shape and its lower edge is pivotally supported by a horizontal shaft 129 carried by brackets 129a and 129b. The bracket 129b has a ratchet 129c thereon adapted to be engaged by the adjacent edge of the door 128. A spring 129d is mounted on the shaft 129 so as to constantly urge 30 the door 128 toward and into engagement with the ratchet 129c. In this manner, the door may be opened to variable extents for draft or peep purposes, and the ratchet 129c will hold the same in such position. A hook-like handle 128a is provided on the upper edge of door 128 to facilitate movement of the latter.

In the operation of the structure so far described, the desired amount of coal, or the like, is placed in the hopper. The hopper 14 and conveyor 16 are set in motion by cutting in the motor 100 in any desired manner, manually or otherwise. Controls (not shown) governed by the temperature of the environment to be heated, or the like, may be employed for cutting in the 40 motor at intervals or for causing it to operate at variable speeds, dependent upon the temperature condition to be maintained. In the rotation of the hopper 14 if it is more than half full of coal, the opening 54 will be constantly supplied 50 with coal which is fed through the conduit 15 by the conveyor 16 at a rate dependent upon the speed of rotation of the hopper 14 and the conveyor. When the level of the coal in the hopper is below the opening 54, the scoop 78 will, as the 55 hopper is rotated, become filled with coal and will deposit the same by gravity when the hopper is rotated to a position such as that illustrated in Figures 1 and 3.

In the rotation of the hopper 14, the coal is 60 shifted and agitated in such a way that it is always in condition for the feeding of substantially uniform amounts. In other words, the opening 54 in the feeding conduit 15 is constantly supplied with fuel so that the conveyor 16, as it 65 is rotated by the hopper, continues to feed the coal along through the conduit to its discharge point in a uniform manner. By agitating and feeding the coal in this manner, either wet, damp or dry coal may be fed uniformly. This feature 70 of the invention makes possible the use of slack or very fine coal with safety and highest efficiency. In the use of slack and very fine coal, particularly where the same must be stored in the home or other similar place, it may become neces- 75

sary to wet or dampen the same to render it safe from the usual combustive dangers. With this invention, the thus dampened coal may be fed with efficiency equal to dry coal because the 5 rotary hopper conditions the same for feeding free from packing, arching and clogging conditions which exist in the use of prior structures, such, for example, as the conventional stoker wherein the hopper is stationary and the coal is 10 fed by gravity to an independently rotated conveyor device. In such prior structures the damp or wet coal, as is well known, tends to pack and arch adjacent to the conveyor to such an extent that either no coal or non-uniform quantities 15 of coal are fed.

Still further, in the use of the structure above described, the agitation of the coal by rotating the hopper reduces abrasive effects on the conveyor and related operating parts to the very minimum so that the length of life of the structure as a whole is greatly increased. In fact, abrasion effects are so reduced that very hard coal and coke 20 may be fed without material wear of the conveyor whereby, contrary to prior efforts, these materials may be used as stoker-fed fuel in a highly practical manner. From practical demonstration, it is believed that the rotary hopper directly driving the conveyor contributes materially in the attaining of the foregoing advantages.

30 In Figs. 12 and 13 I illustrate another form of stoker structure embodying this invention. Specifically, this form includes a frame 130 made up of a plurality of angled pieces. The frame is supported upon front and rear casters 131, 132 which have legs or upright standards 133 adjustably secured and held within the angle legs 130^a of the frame by U-bolts 134. A feed conduit 135 is mounted upon and secured to the front section of the frame 130 by a U-bolt 136 which surrounds the feed conduit and has its ends secured to the upper flange 137 of the front section of the frame (Fig. 13). The rear portion of the feed conduit 135 is supported within a rotatable bearing collar 138 which finds rotatable bearing support within a ring member 139 which is mounted upon and secured to the top flange 140 of the rear frame section by a U-bolt 141 which passes over and around the ring member 139 and is secured to the rear frame flange 140 (Fig. 13).

50 The bearing collar 138 is secured to the rear wall 142 of a fuel-receiving hopper 143. The forward end 144 of the hopper 143 has a bearing collar 145 secured thereto, the latter surrounding and finding bearing support upon the feed conduit 135. The feed conduit 135 extends entirely through the hopper 143 on the axis of the latter and, in the foregoing manner, the hopper 143 is supported for rotation about the feed conduit 135.

55 The hopper 143, like that of the previously described form, is provided with a door 146 through which fuel is fed thereinto. A latch 153 of the form shown in Fig. 12 is employed to hold the door closed.

The feed conduit 135 is provided with an opening 147 within and extending throughout the greater portion of the length of the hopper. The hopper is provided with a shelf or scoop 148 which extends throughout the length of the hopper for feeding coal into the feed conduit opening 147 as the hopper is rotated, as explained in connection with the form of Figs. 1 to 11, inclusive.

70 The rear end of the hopper is provided with a circumferentially-located drive sprocket 149 which is secured to the hopper in any desired manner. This sprocket 149 is adapted to be op-

eratively connected to drive means such as the motor 100 of Fig. 2, or any other suitable drive device.

A screw conveyor 150 is mounted in the feed conduit 135 and it is rotated directly by the hopper 143. The drive connection between the hopper and conveyor is accomplished by a plate 151 secured to the bearing collar 138, the conveyor 150 having a squared end 152 which passes through a similarly shaped opening in the plate 151. Other than the foregoing, the construction and operation of the form of Figs. 12 and 13 is substantially the same as that of Figs. 1 to 11, inclusive.

It is believed that the features and advantages 15 of this invention as first above stated will be readily understood from the foregoing. Also, it is to be understood that while only two forms of structure embodying the invention are shown and described, other changes in details and arrangements of parts may be made without departing from the spirit and scope of the invention as defined by the claims which follow.

I claim:

1. In a coal stoker, a hopper for receiving the 25 coal, a feed conduit extending axially through said hopper and about which said hopper is adapted to rotate, said conduit having an opening therein located within said hopper and through which the coal is fed from the hopper, means for 30 rotating said hopper, a conveyor within said conduit, and means directly connecting said conveyor to said hopper whereby rotation of said hopper imparts feed motion to said conveyor.

2. In a coal stoker, a hopper, a stationary feed 35 conduit, means for rotatably mounting said hopper upon said conduit with the latter on the axis of the former, said conduit communicating with the interior of said hopper, drive means, a conveyor in said conduit, and connections between 40 said drive means, hopper and conveyor whereby rotary motion is imparted to said hopper to in turn impart feed motion to said conveyor.

3. A coal stoker which includes a cylindrical drum-like hopper for receiving the coal, a feed 45 conduit extending entirely through said hopper and on the axis of the latter, said conduit having an opening therein within said hopper, means for rotatably mounting said hopper on said conduit, a rotatable conveyor within said conduit adapted 50 by its rotation to feed the coal through said conduit toward the discharge end of the latter, a connection between said hopper and conveyor for rotating the latter, and means for rotating said hopper.

4. A coal stoker which includes a cylindrical drum-like hopper for receiving the coal, a feed conduit extending entirely through said hopper and on the axis of the latter, said conduit having an opening in its upper side within said 60 hopper, means for rotatably mounting said hopper on said conduit, means in said hopper for collecting coal therein and delivering the same to said conduit through said opening, a rotatable conveyor within said conduit adapted by its ro- 65 tation to feed the coal through said conduit toward one end of the latter, a drive connection between said hopper and conveyor at the drive end of the latter for rotating the conveyor, and means for rotating said hopper.

5. In a coal stoker, a cylindrical hopper, a feed conduit passing through said hopper on the axis of the latter, means for rotatably mounting said hopper on said conduit which includes bearing members on the opposite ends of said 70 75

5 hopper and rotatably mounted on said conduit, a support in which one of said bearing members is journaled, a conveyor in said conduit, said conduit having an opening therein within said hopper, a drive connection between said one bearing member and said conveyor, and means for rotating said hopper which in turn rotates said conveyor through said drive connection.

10 6. In a coal stoker, a frame, a cylindrical drum-like hopper that receives the coal, a feed conduit extending through said hopper on the axis of the latter and having an opening therein within said hopper through which coal is fed thereto from the hopper, bearing members on the opposite ends of said hopper having rotatable connection with said conduit, means adjacent one of said bearing members securing said conduit to said frame, means for rotatably mounting the other of said bearing members on said frame so as to afford rotatable support for said hopper as well as alignment support for said conduit, a screw conveyor in said conduit and having a drive shaft, means affording angular movement of said conveyor connecting the latter to said other bearing member, and means for imparting rotary motion to said hopper to impart rotary feed motion to said conveyor.

15 7. In a coal stoker, a cylindrical coal receiving hopper, a stationary feed conduit passing axially through said hopper and having an opening communicating with the interior of said hopper, means for rotatably mounting said hopper on said feed conduit, means for feeding the coal through said feed conduit, means for rotating said hopper, and means for drive-connecting said hopper to said feeding means.

20 8. In a coal stoker, a cylindrical coal receiving hopper, a stationary feed conduit passing axially through said hopper and having an opening communicating with the interior of said hopper, means for rotatably mounting said hopper on said feed conduit, means in said hopper controlled by rotary movement of said hopper for gathering quantities of coal and delivering the same to said feed conduit, means for feeding the coal through said feed conduit, means for rotating said hopper, and means for drive-connecting said hopper to said feeding means so that said coal feeding means is operated only when said hopper is rotated and at the same rate of speed as the latter.

25 9. In a coal stoker, a cylindrical coal receiving hopper, a stationary feed conduit passing axially through said hopper and having an opening communicating with the interior of said hopper, means for rotatably mounting said hopper on said feed conduit, a scoop member carried by said hopper and actuated in the movement of said hopper to collect a quantity of coal and deliver the same to said feed conduit through said conduit opening during each rotary cycle of said hopper, means for rotating said hopper, means for feeding the coal through said conduit, and means drive-connecting said hopper and feeding means.

30 10. In a coal stoker, a cylindrical drum-like coal-receiving hopper, a stationary feed conduit passing axially through said hopper, means for mounting said hopper on said conduit for rotation thereabout, means for preventing relative axial movement between said hopper and conduit,

5 said conduit having an opening therein and also means for feeding coal therethrough, means for rotating said hopper to agitate and deliver the coal through said opening into said conduit, and means interconnecting said hopper and feeding means whereby the former directly drives the latter.

10 11. A coal stoker comprising a feed conduit, supporting means for said conduit, a hopper rotatable about said conduit and adapted to supply coal thereto, a bearing collar on said hopper and journaled on said conduit, a ring in which said bearing collar is journaled, means for securing said ring to said supporting means, and conveyor means operable within said conduit. 15

15 12. A coal stoker comprising a feed conduit, a cylindrical hopper rotatable about said conduit and adapted to supply the coal thereto, bearing collars secured to the opposite ends of said hopper and which are journaled on said conduit, a ring in which one of said bearing collars is journaled, supporting means, means for securing said ring and a longitudinally-spaced portion of said conduit to said supporting means, and conveyor means in said conduit. 25

20 13. A coal stoker comprising a frame, a feed conduit, means clamping said conduit to the frame, a fuel hopper journaled on said conduit, said conduit having an opening therethrough, said hopper having a shelf therein adapted to 30 elevate coal through rotation, and permit discharge thereof by gravity through said opening into the conduit, a bearing collar on said hopper into which the conduit extends, said bearing collar having a shoulder abutted by the conduit, 35 said bearing collar having a reduced extension, a bearing ring on said extension, clamping means securing the ring to said frame, a plate on the outer end of the bearing collar, and a conveyor connected to the plate and operable in said conduit to feed coal therethrough. 40

45 14. Fuel feeding apparatus of the character described comprising in combination a tubular conveyor including a tube adapted to project into a furnace, a support engaging said tube to hold the same against rotation and in a substantially horizontal position, a rotary hopper drum mounted coaxially on said tube and supported thereby, said tube being open inside said hopper to permit the introduction of fuel thereinto, a 50 rotary screw conveyor inside said tube to advance the fuel thereto and deliver the same to the furnace, means for rotating said hopper, and a plate adjacent the rear side of the drum and carried thereby and connected with said screw conveyor 55 for transmitting rotation to the latter.

55 15. Fuel feeding apparatus of the character described comprising in combination a tubular conveyor including a hollow tube adapted to project into a furnace and through which fuel is 60 adapted to be conveyed and delivered to a furnace, a support connected with said tube to hold the same against rotation and in a substantially horizontal position, a rotary hopper drum mounted coaxially on said tube and having its opposite 65 sides provided with bearing surfaces in engagement with said tube, said tube providing bearing support for each of said bearings, and means for rotating said hopper about the tube.
